BOWLING BALL STORAGE RACK

Richard L. Konves, 34 W. Maxwell Drive, Shelby, Ohio

Filed June 20, 1961, Ser. No. 65,657

Term of patent 14 years

(Cl. D34—5)

The FIGURE is a front perspective view of a bowling ball storage rack showing my design.

The end not shown is like the end shown, while the undisclosed side is plain and unornamented.

I claim:

The ornamental design for a bowling ball storage rack, as shown and described.
